UNITED STATES PATENT OFFICE.

JOHN ISAKSON, OF BONNER, MONTANA.

ROTARY ENGINE.

No. 839,764.

Specification of Letters Patent.

Patented Dec. 25, 1906.

Application filed February 21, 1906. Serial No. 302,169.

To all whom it may concern:

Be it known that I, JOHN ISAKSON, of Bonner, in the county of Missoula and State of Montana, have invented a new and Improved 5 Rotary Engine, of which the following is a full, clear, and exact description.

This invention relates to an engine of the rotary type that is provided with a cylindrical space having a cylinder-head at a point 10 to divide it entirely, so that it forms a partition, and which is also provided with a wheel or disk revolving inside the cylinder and provided with pistons adapted to travel through the cylinder and to slide within the wheel or 15 disk, so as to clear the cylinder-head or partition.

The invention is designed, furthermore, to provide a means outside the casing of the cylinder to slide the pistons in and out at the 20 certain predetermined points.

Reference is to be had to the accompanying drawings, forming a part of this specification, in which similar figures of reference indicate corresponding parts in all the views.

25 Figure 1 shows the engine partly in section and partly in elevation. Fig. 2 is a vertical central section of the engine with the wheel or disk turned to show the pistons in elevation and also showing the partition or cylinder-head in elevation, and Fig. 3 is a perspective view of one of the pistons with the arms for guiding it.

In the accompanying drawings, 10 is a suitable base on which is set the casing 11, both 30 of them being cut out to form a cylinder 12, which can be of any suitable shape in cross-section and is shown in the drawings as rectangular, being oblong. At a suitable point the partition or cylinder-head 13 is shown, 35 which extends down and forms a tight joint with the wheel or disk 14 revolving within the cylinder and rotating therein in a steam-tight closure.

A suitable number of pistons 15, prefer- 45 ably two, are fitted to slide with their supporting rods or fingers 16 in the slots 17. These pistons 15 serve to give motion to the disk 14, and in order that they may be guided in and out, so as to serve as abutments 50 for the steam-pressure, and also to enable them to clear the partition 13, each piston has parallel with the shaft 18 a pin 19, which enters in and is guided by the cam-slot 20^a in the web 20, which is secured to the base 55 10 and casing 11 by bolts 21 or equivalent fastenings. When the pistons 15 and the

disk 14 revolve, the pin travels within the aforesaid slot 20^a, and, as shown in dotted outline in Fig. 1, this ring partakes of a cam nature as it approaches the location radially 60 of the cylinder-head 13, and the pin is drawn in, carrying with it the pistons, and they fit tight down into the wheel 14, as shown in the case of the upper piston in Fig. 2, thereby clearing and passing under the partition or 65 cylinder-head 13. Instead of the cam-slot 20^a the cam-guides 20^b can be arranged on opposite sides of the partition 13, so as to serve the purpose of pushing the pistons 15 inward and holding them inward at the de- 70 sired points.

It will be understood that steam-tight joints would be used where necessary in this engine, so as to prevent leakage of steam.

On each side of the partition 13 and extending in through the casing 11 can be placed the inlets 22, provided with suitable valves, being fed by a main steam-pipe 22^a. The outlets 23 are arranged on either side of the inlets and are also provided with valves. 80 When the engine is expected to be rotated in the direction of the arrow in Fig. 1, the left-hand inlet-valve would be opened and the outlet 23 on the corresponding side closed, and on the other side of the cylinder-head 85 the inlet 22 would be closed and the outlet 23 opened. Now as the wheel or disk, with its pistons, rotates it is driven by the pressure of the steam, which has a steady flow in the direction of the arrow, and it receives full 90 pressure until it has passed around it where the slot 20^a commences to leave a true circular path, and it is then drawn inward by the cam shape of the slot 20^a in the casing, whereby it opens to allow the steam to pass around 95 from in front of it toward the outlet 23 on the right-hand side, the piston being drawn in, as above described, to clear the cylinder-head 13, and when it goes beyond the cylinder-head it commences to project again into the cylinder and by the time it projects fully into the cylinder 12 it takes up the full force of the steam, thereby relieving the other piston, which in turn goes through the same performance. In this way we have constantly 100 a piston receiving the full pressure of the steam, and these pistons also clear the cylinder-head, making a smooth-running engine. It will also be obvious that by a reversal of the opened and closed inlets and exhausts 105 the direction of rotation of the engine can be reversed.

Having thus fully described my invention, I claim as new and desire to secure by Letters Patent—

A rotary engine comprising a casing inclosing a cylinder, a partition entirely closing the cylinder, a wheel arranged to revolve within the casing and the cylinder, pistons carried by the wheel or disk, fingers secured to the pistons and arranged to slide in slots

in the wheel or disk, a pin on one of the fingers, a ring secured to the casing having a slot to receive the pin, the ring being of such shape as to withdraw the piston when passing the partition.

JOHN ISAKSON.
